APPARATUS FOR HANDLING PATIENTS

George I. Rockwood, Worcester, Mass.

Application May 7, 1947, Serial No. 746,423

5 Claims. (Cl. 5—36)

1

This invention relates to apparatus particularly designed for use in hospitals and rest homes in which sick or feeble patients must be lifted, turned or moved. These handling operations are commonly performed manually, and the assistance of several persons may be required if the patient is very heavy or if movement of the patient is unusually painful.

It is the general object of this invention to provide improved apparatus by which a patient of any weight may be comfortably lifted, turned or moved to a new location by a single attendant and without undue effort.

To the attainment of this general object, I provide a light but rigid frame which is open at one side, so that the base of the frame may be moved under the patient's bed and so that the offset upper end portion of the frame will overlie the patient.

Further features of the invention relate to improved supporting devices for the patient; to improved lifting, turning and holding mechanism; and to the provision of reliable and effective safety devices.

My invention further relates to arrangements and combinations of parts which will be herein-after described and more particularly pointed out in the appended claims.

A preferred form of the invention is shown in the drawings, in which:

Fig. 1 is a front elevation of my improved handling apparatus;

Fig. 2 is a plan view thereof;

Fig. 3 is an end elevation, looking in the direction of the arrow 3 in Fig. 1;

Fig. 4 is a detail front elevation of a drum and belt connection, looking in the direction of the arrow 4 in Fig. 3;

Fig. 5 is a transverse sectional elevation, taken along the line 5—5 in Fig. 4;

Fig. 6 is a detail view of a supporting loop or sling, looking in the direction of the arrow 6 in Fig. 1; and

Fig. 7 is a detail side view of an auxiliary belt.

Referring to the drawings, my improved handling apparatus comprises a rigid framework F (Figs. 1 and 2) having head and foot end frame members 10 and 11 rigidly secured together by a plurality of spacing tubes 12 and bolts 14. Each frame member, as 10 (Fig. 3), comprises an upright front portion 16, a rearwardly projecting lower arm or base member 17, and a rearwardly projecting upper arm 18. These frame members are preferably made of light cast metal, as aluminum, and are also preferably

2

made in three separate parts for convenience in casting.

The rear sides of the frame members 10 and 11 are entirely open, so that the apparatus may be pushed under and receive a bed, as indicated diagrammatically at B in Fig. 3.

The framework F is normally supported on spaced swivel casters 20 in the frame member 10 and on a single caster 21 on the frame member 11. The caster 21 is mounted near the middle of the lower arm 17 of the frame member 11, so that the apparatus has a three-point support only and may be easily shifted in any desired direction.

It is at times desirable to hold the framework stationary and to prevent accidental shifting thereof, and for this purpose I provide a locking device comprising a plunger 25 (Fig. 3) slidable at its lower end in a lug 26 on the frame 10 and having its upper end pivoted at 27 to a handle 28 mounted on a fixed stud 29. When the handle 28 is swung upward against a stop pin 30, the plunger 25 is pushed downward and the pivot 27 passes beyond the dead center. This depresses the plunger 25 sufficiently to raise the front caster 20 off of the floor, and a front corner of the framework F is then supported on the lower end of the plunger 25, which prevents displacement thereof.

30 A lever 32 is pivoted at 33 to the rear portion of the lower arm 17 of the frame member 10 and is connected by a link 35 to a bell crank 36 mounted on a fixed pivot 37 and having an arm 38 engaged by a collar 39 on the plunger 25.

35 A spring 40 normally swings the lever 32 clockwise and out of supporting position when the plunger 25 is lifted by the handle 28. When the plunger is depressed, the lever 32 is swung to the position shown in Fig. 3 and thus provides a second stationary point of support for the apparatus framework.

40 Parallel shafts 42 and 44 (Fig. 2) are mounted in spaced bearings 45 on the upper arms 18 and 18a of the end frame members 10 and 11. Gears 47 and 48 are fixed to the shafts 42 and 44 and are intermeshed so that the shafts are rotated in opposite directions.

45 A crank 50 is mounted on a crankshaft 51, and a pinion 52 fixed on the shaft 51 engages a gear 53 fixed on a short shaft 54. A pinion 55, also fixed on the shaft 54, engages the gear 48 previously mentioned.

50 A power-multiplying train of gearing is thus provided by which the shafts 42 and 44 may be

rotated by turning the crank 50 to raise or lower the patient as desired.

A ratchet 57 (Fig. 3) fixed on the end of the crank shaft 51 is engaged by a locking pawl 58 which rests by gravity on the ratchet 57. The pawl 58 thus holds the load in any desired position and prevents lowering of the load except after manually lifting the pawl 58. The pawl and ratchet thus constitute a safety device which will hold a patient in any desired elevated position and which will prevent any accidental drop of a patient.

Drums 60 are fixed to the shafts 42 and 44 and are provided with means for attaching the two ends of a body-supporting belt 62 thereto. Smaller drums or pulleys 65 are also secured to the shafts 41 and 42 and loops or slings 66 and 67 are connected by chains 68 to the pulleys 65, so that these loops or slings will be raised simultaneously with the lifting of the body-supporting belt 62.

Special provision is made for lifting the head and shoulders of the patient at the same time that the body portion and legs are lifted. For this purpose a swinging tubular member 70 (Fig. 2) is mounted in bearings in the upright portions 16 and 16a of the end frame members 10 and 11. The swinging end portion of the member 70 is bent rearward as indicated at 70a, and the extreme rear end portion of the part 70a is angularly offset as indicated at 70b.

The offset portion 70b is connected by a chain 72 to a pulley 73 fixed on the end of the lifting shaft 42. Consequently the member 70 will be swung upward about its front bearing portion as the lifting tackle of the apparatus is raised.

A head-rest frame 80 has a loose swivel connection at 81 to the portion 70a of the swinging member 70. The free ends of the frame 80 are detachably connected by chains 82 to the pulleys 73 on the shafts 42 and 44. A head-rest 85, preferably of canvas, is mounted in the frame 80 and may be suitably secured thereto.

With the construction shown, the spaced ends of the head frame 80 will be raised by the chains 82 as the shafts 42 and 44 are simultaneously rotated in opposite directions, and the middle portion of the member 80 will be raised on its swivel support 81 as the end portion 70b of the tubular member 70 is swung upward by its chain 72.

If the middle portion of the frame 80 is supported on the back of a chair as a patient is being lowered, the spaced end portions of the frame 80 and the wider part of the head-rest 85 will be lowered with the patient, while the middle portion of the frame and head-rest remain raised. A patient may thus be easily deposited in a sitting or reclining position.

Special provision is made to prevent accidental disengagement of the ends of the body-supporting belt 62 from the drums 60. For this purpose, headed studs 90 (Figs. 4 and 15) are fixed in recessed portions 92 of the drums 60 and are adapted to receive rings 94 connected by links 95 to a cross pin 96 mounted in the spaced and looped ends 97 of the belt 62. A latch 100 is pivoted in an extension 101 of the recess 92, and this latch has a headed stud 102 extending through a slot in the drum 60 and provided with a coil spring 103.

In order to release the ring 94 from the headed stud 90, it is necessary for the operator to reach inside of the drum 60 and press the stud or plunger 102 outward to raise the latch 100.

Consequently the ring 94 cannot be accidentally displaced from the stud 90.

A second stud 90a and latch 100a are provided at the opposite side of the drum 60 and in reverse position. The stud 90 is used on both drums when it is desired to raise or lower the patient, but the ring 94 at one end of the body-supporting belt 62 is placed on a stud 90a when it is desired to raise one end of the belt and to simultaneously lower the other end for turning instead of lifting the patient.

One end 62a (Fig. 3) of the belt 62 may be connected to the associated link 95 through a friction device 110, so that the length of the belt may be conveniently adjusted. The device 110 may be of any usual commercial form.

Having described the details of construction of my improved handling apparatus, the operation and advantages thereof will be readily understood. If it is desired to lift the patient, the apparatus will be moved up to the side of the bed as indicated in Fig. 3, with the lower arms 17 extending freely under the bed.

While the patient is lying extended on the hospital bed B, a narrow belt 120 is first passed by hand under the patient's shoulders, with the ends pulled up below the armpits and connected temporarily to the chains 82. The nurse then applies lifting power to the upper part of the patient by turning the crank 50, which oppositely rotates the shafts 42 and 44.

Space is thus provided under the patient's head and shoulders, and this space permits the belt 62 to be passed under the patient. The end 62a is then inserted through the friction device or clamp 110 and the belt is thus adjusted and secured.

The space so obtained also provides clearance under the head and shoulders for inserting the canvas portion 85 of the head-rest member 80. The middle portion of the frame 80 is then placed on the swivel connection 81.

The patient is then lowered to the bed B to relieve the tension on the chains 82, which are then unhooked from the narrow belt 120 and are connected to the ends of the head-rest frame 80 as shown in Fig. 2. The loops or slings 66 and 67 are then passed over the patient's legs and feet and are connected to the chains 68.

The handle 50 can then be rotated to turn the shafts 42 and 44 and raise the patient to provide any desired clearance between the patient and the bed B, so that a sheet may be changed or any other desired procedure may be carried out.

While thus elevated, the patient is very comfortably supported both as to body, legs, head and shoulders. While thus supported, the apparatus may be drawn forward away from the bed and the patient may be rolled to a new location and may be deposited on a bed or couch or in a reclining chair.

The locking pawl 58 retains the lifting mechanism until the pawl is intentionally lifted away from the ratchet 57 by the operator. If the operator lets go of the pawl 58 accidentally, the pawl immediately drops to locking position and prevents further downward movement of the patient.

If it is desired to turn instead of raise the patient, one end of the belt 62 is connected to the stud 90a at the inside of the drum 60 instead of to the stud 90 at the outside. This end of the belt 62 will then be lowered as the other end of the belt is simultaneously raised, thus turning the patient on the bed but without elevating the

patient above the bed. Obviously the patient may be turned in either direction by selecting the proper end of the belt 62 for connection to the inside stud 90a.

After the desired handling operations, such as lifting, turning or transporting, have been performed and the patient has been placed in a desired position, the body-supporting belt and the loops or slings are readily disconnected and the apparatus may be removed for use in some other location.

Having thus described my invention and the advantages thereof, I do not wish to be limited to the details herein disclosed, otherwise than as set forth in the claims, but what I claim is:

1. In an apparatus for handling patients comprising a frame open at one side to receive a bed and having longitudinally spaced overhanging head and foot end members, transversely spaced bearings on said members, parallel main shafts rotatably mounted in said bearings, patient-contacting handling tackle mounted on and connected to said shafts, means to simultaneously rotate said shafts to raise at least a portion of said handling tackle and means to lock said rotating means, that improvement in which the handling apparatus includes a belt to underlie the lower part of the back of the patient, a separate head-supporting structure, means to move that inner edge portion of said head-supporting structure which is nearer said belt upward and downward simultaneously with said belt, and additional means to move the outer edge portion of said structure upward simultaneously with said first-mentioned edge portion, but said additional means including a flexible element and permitting independent downward movement of said first-mentioned edge portion when said outer edge portion is held from downward movement.

2. The combination in an apparatus for handling patients as set forth in claim 1, in which the first mentioned means to raise the head supporting structure comprises a bar pivotally mounted parallel to said main shafts in bearings in said end frame members and having a transversely extending end portion projecting substantially beyond and across the head end frame member and in which said transverse end portion of said bar has a return end part extending toward said head end frame member, and in which the additional means comprises a chain effective to raise the return end part of said bar with said belt, and in which pivotal means connects the outer edge portion of said head-supporting structure to a point in the transverse end portion of said bar.

3. In an apparatus for handling patients comprising a frame open at one side to receive a bed and having longitudinally spaced overhanging head and foot end members, transversely spaced bearings on said members, parallel shafts rotatably mounted in said bearings, patient-contacting handling tackle mounted on and connected to

said shafts, means to simultaneously rotate said shafts to raise at least a portion of said handling tackle and means to lock said rotating means, that improvement which comprises drums on said parallel shafts, a belt located to underlie the lower part of the back of a patient to be handled, means to detachably connect the ends of said belt to said drums at predetermined points, additional means to connect either end of said belt to its associated drum at a point circumferentially and substantially spaced from said first-defined point of connection and with said belt extending circumferentially from said point of attachment in the reverse direction, and means to lock both ends of said belt to said drums in either operative position.

4. In an apparatus for handling patients comprising a frame open at one side to receive a bed and having longitudinally spaced overhanging head and foot end members, transversely spaced bearings on said members, parallel shafts rotatably mounted in said bearings, patient-contacting handling tackle mounted on and connected to said shafts, means to simultaneously rotate said shafts to raise at least a portion of said handling tackle and means to lock said rotating means, that improvement which comprises drums on said parallel shafts, headed studs fixed in said drums to detachably receive the ends of said handling tackle, and spring-closed latches effective to lock said ends from accidental disengagement with said headed studs.

5. In an apparatus for handling patients comprising a frame open at one side to receive a bed and having longitudinally spaced overhanging head and foot end members, transversely spaced bearings on said members, parallel shafts rotatably mounted in said bearings, patient-contacting handling tackle mounted on and connected to said shafts, means to simultaneously rotate said shafts to raise at least a portion of said handling tackle and means to lock said rotating means, that improvement which comprises drums on said parallel shafts, studs fixed in peripheral recesses in said drums at circumferentially and substantially spaced points on the drum surfaces, said studs selectively and detachably receiving the ends of said handling tackle, and safety devices effective to prevent accidental detachment of said ends from said studs.

GEORGE I. ROCKWOOD.
